UNITED STATES PATENT OFFICE

91,505

DESIGN FOR A CASKET

Orien S. Strickland, Portales, N. Mex.

Application October 26, 1933. Serial No. 49,566

Term of patent 14 years

To all whom it may concern:

Be it known that I, ORIEN S. STRICKLAND, a citizen of the United States, and resident of Portales, in the county of Roosevelt and State of New Mexico, have invented a new, original, and ornamental design for a Casket, of which the following is a specification, reference being had to the accompanying drawing forming part thereof, in which

Figure 1 is a perspective view of the invention with the cover raised to show the interior of the casket as exhibited in use, and showing in dotted lines a removable section or side piece in place, said side piece being removed and laid aside out of sight when the casket cover is raised and the casket is exhibited and in use.

Figure 2 is a similar view of the casket with said side section in place and the lid closed.

I claim:

The ornamental design for a casket, as shown, and described.

Dated October 2, 1933.

ORIEN S. STRICKLAND.
